F. F. Cornell Jr

Brick Machine.

No 66,800.

Patented July 16, 1867.

United States Patent Office.

FREDERICK F. CORNELL, JR., OF NEW YORK, N. Y.

Letters Patent No. 66,800, dated July 16, 1867.

IMPROVED BRICK MACHINE.

The Schedule referred to in these Letters Patent and making part of the same.

TO ALL WHOM IT MAY CONCERN:

Be it known that I, FREDERICK F. CORNELL, Jr., of the city, county, and State of New York, have invented certain new and useful Improvements in Brick Machinery; and I do hereby declare that the following is a full, clear, and exact description of the same, reference being had to the accompanying drawings, making part of this specification.

The object of this my invention is—

First. To provide moulds that may be arranged in a nest or hollow circle, so that the same, when placed in a horizontal position, may be filled by the unpressed material flowing into the empty mould from the upper side, after which the compression is effected by a plunger moved horizontally inwards by any suitable power.

Second. Providing a bed-plate, upon which that portion of the nest containing the mould in which pressure is to be exerted may rest, and furnishing said bed-plate with a roller to support the back of the mould, and with studs extending upwards at either side of the mouth of the mould, and at its outer edge, and firmly connected above said nest of moulds to the axis of the aforesaid roller, and jointing to said studs a hanging jaw with a suitable face to cover the upper open side of the mould, and with lugs extending downward and back of said studs, so that the fulcrum points, by which pressure is exerted through the plunger, may be located in said lugs, and opposite to and in a horizontal line with the centre of the plunger, so that the greater the pressure on the face of the plunger, the greater will be the pressure of the face of the jaw upon the top of the mould, thereby enabling the moulds to move freely from under the same when free from pressure, and preventing any feather-edge from forming upon the upper side or edge of the brick when pressure is applied.

Third. Forming the back and one side of the mould in a separate piece, so that the same can be moved outward and discharge the brick, and, by moving slightly away from the fixed end of the mould, allow of such removal without any pressure upon the ends or sides of the finished brick.

Fourth. Furnishing the under side of the nest of moulds with a flange, in which suitable notches may be made, with which an index-bar, moving in the bottom of the bed-plate, may engage, for the purpose of holding firmly the nest of moulds while the plunger is performing its function, and for the further purpose of bringing the mouth of the mould exactly opposite to the face of the plunger before the same commences to move.

In the accompanying drawings—

Figure 1 is a vertical section taken in the lines *y y* of fig. 2.

Figure 2 is a horizontal view showing, as also does fig. 1, in red lines, a complete nest of moulds with a lever attached to the plunger.

Figures 3, 4, and 7 are horizontal views of the mould, with its block and gate in their three different positions, viz, fig. 7, gate shut and mould ready to receive loose material; fig. 4, gate open and held by stoppin, and plunger entering to compress the loose material; and fig. 3, mould-block pushed forward to discharge the finished brick.

Figure 5 is a horizontal view of the index-bar.

Figure 6 is a vertical section taken in the line *z z* of fig. 7, through the nest of moulds.

Figure 8 is a horizontal view of the under side of the mould-table.

Like letters and numerals are used to designate like parts in each of the figures.

The cast-metal bed-plate *A* is constructed of sufficient width and length to give a rest for that portion of the nest of moulds containing the filled mould or moulds in which pressure is to be applied, and to give support and firmly retain in position the standards *T T* and axis *C* of the roller *B*. It is also provided with an open and circular groove, *i*, crossed at right angles by the groove *h*, into which passes and rests the pointed index-bar *H*. The nest of moulds consists of six or more, arranged in a hollow circular table, one entire mould being shown with the nest extending in red lines in figs. 1 and 2. Each mould is formed as follows: The bottom by the circular plate *I*, the one end by the fixed block *K*, the back and other end by the movable mould-block *M*, the front by the gate *P*, when moving from the point where it is filled until it comes opposite the plunger *L*, which, during the operation of the pressing, forms the front of the mould, and the top of the mould, during pressure, is formed by the face *e* of the jaw *E*. The mould-block is retained in position by the bevels *j j* and the fixed blocks *K K*. The gate *P* is retained in position and allowed to open and shut by means of the dove-

tailed slip p , firmly attached thereto, moving in a corresponding dove-tail groove, p' , in the block K . Being closed during the operation of filling the mould, it carries the material in the mould around until the notch s in its end, engaging with the stop-pin r in the standard T , as shown in fig. 4, allows the nest of moulds to move forward, and the gate is held stationary. The jaw E is constructed of cast metal, and is firmly attached to the standards T T by the bolt F . When the lugs G G are drawn upon at the fulcrum point g g , the face e rests firmly on top of the mould, and closes the upper side, through which the clay is introduced. The plunger L rests loosely between the standards T T , and may be operated by any suitable power which may have its fulcrum point attached to the lugs G G at the points g g . The axis C is furnished with a cross-head, D , which is firmly secured to the standards T T by the bolts m m passing over the nest of moulds and the face of the jaw E . The mould-block M is furnished with a pin, n , on its upper and inner edge, to enable any proper mechanism to return it to its first position after moving outward, as shown in fig. 3.

The operation of my improved brick machinery is as follows: The clay or material to be pressed into a brick or block having been filled into the mould by any suitable machinery, which filling process may be going on in some one of the moulds in the positions 4, 5, or 6, as shown in red lines, all the time, the gate P being closed, as shown in fig. 7, in case said gate be used, which, however, is not necessary, as the material may be retained in the moulds by other means, the nest of moulds is then moved forward, so that a filled mould is brought opposite to the plunger L . In order to do this, the stop-pin r is withdrawn before the nest begins to move, and is held by any proper mechanical device until the gate P , to be opened, comes opposite, when it is allowed to engage with the notch s , and the mould moving forward, the gate is retained and the mouth of the mould is left open to receive the plunger L , as shown in fig. 4. Immediately before the plunger begins to move, the index-bar H is rapidly moved forward in its groove h , so that its pointed end enters and passes through the notch v in the flange i , (shown in fig. 8,) and by this device the said notch v being so adjusted (fig. 7) that when the index H has passed through it, the mould mouth above is in exact position to receive the plunger L , any inequality in the power moving the nest of moulds is rectified. As soon as the mould is in position, the plunger L is moved forward by a lever, 7, as shown in red lines in figs. 1 and 2, or by any other proper mechanical contrivance for that purpose having the fulcrum points at g g . The face e of the jaw E is, by this means, drawn firmly down upon the upper side of the mould, as shown in fig. 1, and the force with which it presses down is in exact proportion to the resistance to the entrance of the plunger into the mould. The brick or block having been pressed and the plunger having been withdrawn and taken the position shown in fig. 1 by blue lines, the jaw E is allowed to rise off the mould, as shown also in blue lines, leaving the nest free to move forward until another filled mould is presented for the action of the plunger, and during the next pressure the brick that has been formed is moved out by the mould-block M being pushed outward by any proper application of power, as shown in fig. 3, and the said block, after the brick is discharged, is returned to its original place by means of power applied to the pin n , and is ready to receive another charge. The mould-block M , on the edge f f' , is bevelled inwards, so that the instant it starts the pressure on the end of the brick is removed. The fixed blocks K K are bevelled inwards on their upper faces, as shown in fig. 6 at R , so that any clay that may have accumulated will be discharged inwards, so as to leave a clear surface to pass under the face e of the jaw E .

What I claim as new, and desire to secure by Letters Patent, is—

1. A mould, for forming bricks or blocks, open on two of its contiguous sides.
2. The movable mould-block M , with its outer side f tapered inwards in a direction opposite to its motion when discharging a finished brick, and retained in position by the fixed block K , having a corresponding taper at f' , and by ribs j j , attached to the fixed blocks K K .
3. The gate P , or its equivalents, provided with the dove-tail slip p , moving in the dove-tail groove p' , in the side of the fixed block K , as and for the purposes hereinbefore described.
4. The bed-plate A , standards T T , spindle C , supporting-roller B , cross-head D , bolts m m , groove h to receive the index-bar H , and groove e to receive the flange i , as and for the purposes hereinbefore described.
5. The index-bar H , with a suitably bevelled end, moving in proper guides to engage with the notch v in the flange i , or with any other mechanical device, in combination with a movable table or nest of moulds, as and for the purposes hereinbefore described.
6. The swinging jaw E , having lugs to which may be attached the rods or frame furnishing resistance to the power used for moving the plunger forward when pressing a brick, as and for the purposes hereinbefore described.
7. Bevelling the upper faces of the fixed blocks K , as and for the purposes hereinbefore described.
8. The bed-plate A , plunger L , index-bar H , mould-table I , flange i , notch v , supporting-roller B , cross-head D , and bolts m m , standards T T , and head-bolt F , all arranged as and for the purposes hereinbefore described.
